UNITED STATES PATENT OFFICE.

WIGO G. NYMON, OF ARGUSVILLE, NORTH DAKOTA.

WRENCH.

1,158,713.

Specification of Letters Patent. Patented Nov. 2, 1915.

Application filed February 2, 1915. Serial No. 5,754.

To all whom it may concern:

Be it known that I, Wigo G. Nymon, a citizen of the United States, residing at Argusville, in the county of Cass, State of North Dakota, have invented certain new and useful Improvements in Wrenches; and I do hereby declare the following to be a full, clear, and exact description of the invention, such as will enable others skilled in the art to which it appertains, to make and use the same.

This invention relates to certain novel and useful improvements in wrenches.

An object of the invention resides in the provision of a wrench which will be quickly and easily adjusted to various sizes and which will be automatically held in any of its adjusted positions.

A further object of the invention resides in the construction of a wrench in such manner that the adjustment thereof may be exceedingly fine.

With these and other objects in view, such as will appear as the description progresses, my invention comprises the combination and arrangement of parts as set forth in and falling within the scope of the appended claims.

Referring to the drawing: Figure 1 is a longitudinal sectional view of my device, showing the position of the several operating parts. Fig. 2 is a transverse sectional view on line 2—2 of Fig. 1. Fig. 3 is a view similar to Fig. 1, showing the position of the locking slide when the movable jaw is being adjusted. Fig. 4 is a fragmental detail showing the shank gripping means.

Referring to the drawing wherein like parts are indicated by like characters throughout the several views: The embodiment of my device shown in drawing consists of a body portion 5 having detachably secured to one end thereof a handle 6 and formed integrally at the other end a stationary jaw 7. Extending longitudinally of the body portion is a rectangular hole 8 which is enlarged at one end to form a chamber 9 and opens, as at 10, through the face of the stationary jaw 7. Slidably mounted in the hole 8 and extending through the chamber 10 is a rectangular shank 11 having a movable jaw 12 formed on one end thereof adjacent the stationary jaw 7 and a head 13 on the other end thereof. The end 55 of the shank 11 on which the head 13 is formed projects outwardly from the body

portion 5 and into a chamber 14 in the handle 6, which chamber has at one end an enlarged portion 15 for a purpose which will later appear.

In order that the shank 11 may be gripped so that the jaw 12 will be maintained at any desirable distance from the jaw 7, I have provided in one wall of the chamber 9 a gripping plate 16 which has teeth on its face adapted to bite into the adjacent face of the shank 11. On the other side of the shank 11 the wall of the chamber is inclined, as at 17, and in this portion of the chamber is a slide 18 having a beveled end 19 for engaging the inclined portion 17 of the adjacent wall of the chamber. In the face of the slide 18 is a gripping member 20 which is likewise adapted to bite into the shank 11. The beveled end 19 of the slide 18 is normally held in engagement with the inclined portion 17 by means of a coil spring 21 which is positioned on a pin 22 on one end of the slide and on a second pin 23 on the body portion 5 within the chamber 9, the width of this slide 18 is slightly less than the distance between one face of the shank 11 and the adjacent face of the chamber 9 for a purpose which will later appear.

Secured to the slide 18 and extending outwardly from the body portion 5 through a slot 24 is an operating handle 25 which when operated to compress the spring 21 will release the gripping action on the shank 11 and allow the said shank to slide within the hole 8. In order that this shank may be projected outwardly from the body portion, I have provided a coil spring 26 within the hole 14 in the handle 6 which bears against the under face of the collar 13.

In order that the shock incident to the pushing of the shank 11 outwardly by the spring 26 may be taken up, I have provided a spring 27 which encircles the end of the shank 11 and is adapted to be engaged by the collar 13 on the shank 11 when the collar reaches the said spring in its movement through the hole 14.

In operation assuming that the jaws 7 and 12 are in contact so that the wrench is closed and it is desired to adjust the same to fit a particular nut, the handle 25 is operated so as to compress the spring 21 and draw the gripping member 20 away from the shank 11. The spring 26 then causes the jaw 12 to be pushed outwardly from the jaw 7. At this time the collar 13 will move into en-

gagement with the spring 27 and spring 27 will take up the shock incident to the movement of the jaw 11. The handle 25 may then be released and the movable jaw 12 pushed inwardly until the proper adjustment is obtained. The inward movement is allowed by the particular construction of the teeth on the gripping members 16 and 20 and because of the arrangement of the beveled end 19 of the slide 18 and the inclined portion 17 of the chamber wall. When the jaw has been moved in the proper distance so that it will grip the nut which is to be turned it will be prevented from moving outwardly because of the biting action of the gripping members 16 and 20 and because of the fact that any tendency to push the shank 11 outwardly will also tend to bind the slide 18 more firmly against the shank 11. It will thus be seen that I have provided a wrench which will be quickly and easily adjusted and one wherein the movable jaw is moved outwardly automatically from the stationary jaw upon the release of the locking pawl. I have further so constructed the device that any tendency to move the jaws apart during operation will only more firmly bind the locking member against the shank of the movable jaw. While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the invention or exceeding the scope of the appended claims.

What I claim is:—

1. In a wrench, a body portion having a stationary jaw on one end thereof, a shank slideable through said body portion and having a jaw on one end thereof, means to lock the shank within the body portion, and means to automatically project the shank outwardly from the body portion upon the release of the locking means and resilient means for absorbing shock incident to said projecting of the shank. 40
2. In a wrench, a body portion having a chamber therein, and a hole extending therethrough, one wall of the said chamber having an inclined portion, a slide mounted within the chamber and having a beveled end adapted to ride on said inclined face, a gripping member on the opposite face of said chamber, a gripping member on said slide, a shank passing through said body portion between said gripping members and having a jaw on the outer end thereof, resilient means for moving said beveled end of the slide in engagement with the inclined portion of the wall of the chamber to cause the gripping members to bite into the said shank, resilient means for projecting the said shank outwardly from the body portion upon the release of the locking means, and resilient means for limiting the outward movement of the shank and absorbing the 70 shock incident thereto. 50

In testimony whereof, I affix my signature, in the presence of two witnesses.

WIGO G. NYMON.
